Attorney—

UNITED STATES PATENT OFFICE.

GEORGE F. RICHARDSON, OF MARTINSVILLE, INDIANA, ASSIGNOR TO EDWIN L. BROWN, OF SAME PLACE.

DESIGN FOR A CHAIR.

SPECIFICATION forming part of Design No. 24,389, dated June 11, 1895.

Application filed May 13, 1895. Serial No. 549,192. Term of patent 3½ years.

To all whom it may concern:

Be it known that I, GEORGE F. RICHARDSON, a citizen of the United States, residing at Martinsville, in the county of Morgan and State of Indiana, have invented and produced a new and original Design for Chairs; and I do hereby declare the following to be a full, clear, and exact description of the invention, such as will enable others skilled in the art to which it applies to make and use the same.

The leading features of my design are in those parts which are above the seat portion of the chair. The two front legs A, A, extend vertically from the floor to their intersection with the seat and from thence are bent outwardly. The back legs or posts B, B, starting from the floor are carried approximately in a vertical direction until they meet the seat and are thence curved outwardly and finally make a return bend and extend a short distance in an approximately vertical direction. A continuous oval shaped cross bar C is applied to the upper ends of the posts B, B, the curved ends of the oval extending beyond the posts in the manner clearly shown in the drawing. The space between the sides of the oval and of the posts is filled in with woven splint work E. The bent bar F starts from a point in front and below the upper end of the post A, curves back over the top of the post and above same and then forms a horizontal horse shoe curve

passing in front of and contacting with the posts B, B, and terminating in front of the opposite post A in a manner similar to its departure from the first post A. F' is a curved bar having its ends terminating on the inside of the posts A, A, and contacting with the back posts B, B. F² is a short curved bar connecting the two back posts and placed above the bar F. Its ends overlap the bars B, B. The space between the bars F and F' and between the bars F and F² is filled in with woven splint work to within a few inches of the posts A, A, which spaces are left open. The seat G is of woven splint work.

The posts, bars and rounds are all covered with the natural bark of the second growth hickory and may be notched through the bark as shown at n so as to expose the light colored under wood.

The same design can be used for chairs with and without rockers.

What I claim is—

The design for a chair, substantially as shown and described.

In testimony whereof I affix my signature in presence of two witnesses.

GEO. F. RICHARDSON.
